[57] CLAIM

The ornamental design for a towed plume target, as shown and described.

DESCRIPTION

FIG. 1 is a perspective view of a towed plume target showing my new design;

FIG. 2 is a perspective view looking from the under side of FIG. 1;

FIG. 3 is a side elevational view, the side not shown being a mirror image of the side shown;

FIG. 4 is an end view looking from the left of FIG. 3;

FIG. 5 is an end view looking from the right of FIG. 3;

FIG. 6 is a top plan view thereof; and,

FIG. 7 is a bottom view thereof.
